UNITED STATES PATENT OFFICE.

PETER T. POTTS, OF CHICAGO, ILLINOIS, ASSIGNOR TO THE VORTEX MANUFACTURING CO., A CORPORATION OF ILLINOIS.

CUP-ASSEMBLING ATTACHMENT FOR CUP-FORMING MACHINES.

Application filed January 17, 1921, Serial No. 437,834. Renewed November 23, 1922.

To all whom it may concern:

Be it known that I, PETER T. POTTS, a citizen of the United States, and a resident of the city of Chicago, in the county of Cook and State of Illinois, have invented certain new and useful Improvements in a Cup-Assembling Attachment for Cup-Forming Machines; and I do hereby declare that the following is a full, clear, and exact description of the same, reference being had to the accompanying drawings, and to the numerals of reference marked thereon, which form a part of this specification.

This invention relates to an improved device for use with cup forming machines or the like, wherein a cup of paper or some similar material is formed from a prepared blank upon dies or forms in the machine, and has for its object the provision of a receptacle to receive and assemble the finished cups made by such means after they have been discharged from the forming dies. In the form of the invention as herein disclosed, the receiving tube is adapted particularly for the reception and automatic stacking of conical paper cups or liners such as are commonly used in connection with conical metallic holders used for dispensing sodas and other like beverages. These conical cups are preferably formed of paraffin saturated paper blanks and are formed into shape, to correspond with the conical metallic holders, in a machine provided therefor. After the cups have been formed they are automatically ejected from the machine and formerly were received and immediately assembled by an extra operator in order to prevent them from accumulating in quantities which would be unmanageable.

One of the objects, therefore, of this invention is the provision of a receiving tube for such paper cups or other formed articles wherein they are automatically assembled as they are ejected from the machine.

Another object of the invention is the provision of a receiving tube for cups or the like which is provided with a movable cup support, the said support being adapted to be automatically moved downwardly a predetermined distance every time a cup is delivered into the tube.

A further important object of the invention is the provision of a receiving tube with a movable support so arranged that the

cup or other object fed thereto is delivered to the top of the tube and automatically stacked or "nested" at that point in connection with similar cups, thereby preventing any irregular stacking which would result if the single cups were dropped to the bottom of the tube.

Another and further important object of the invention is the provision of a receiving tube for cups or like receptacles which is adapted to be used in connection with a cup forming machine and which when filled may be readily removed and the finished cups taken therefrom in assembled position ready to be packed or placed into a shipping container and at the same time may be conveniently replaced by a similar tube to immediately receive a further supply of cups.

Other and further important objects of this invention will be apparent from the disclosures in the specification and the accompanying drawings.

The invention (in a preferred form) is illustrated in the drawings and hereinafter more fully described.

On the drawings:

Figure 1 is a side view, partly in section, of a machine for forming conical paper cups with the improved receiving tube of the invention applied thereto.

Figure 2 is a detail view of a portion of the front of the machine showing a part of the actuating mechanism for the receiving tube as applied thereto.

Figure 3 is a top view, partly in section, of the receiving tube and its accompanying mechanism, taken on the line 3-3 of Figure 1.

Figure 4 is a side elevation, partly in section, of the pulley or drum of the device together with its connected gear wheel and pawls.

Figure 5 is a sectional view taken on the line 5-5 of Figure 1 looking in the direction indicated by the arrows.

Figure 6 is a sectional view taken on the line 6-6 of Figure 3.

As shown on the drawings:

The reference numeral 10 indicates in a general way the cup forming machine to which the invention is applied, said machine being equipped with a pair of cup forming dies 12 and 14 upon which a conical paper

cup is formed. The particular cup forming machine to which the invention is shown as applied forms no part of the present invention but is embodied in the applicant's copending cases Serial Nos. 437,832 and 437,833, filed January 17th, 1921.

A bracket or extending arm 16 is fixed to the front part of the machine 10 and is adapted to hold in position a delivery chute 18, as shown in Figure 1, which receives the cups 20 as they are discharged from the forming cones 12 and 14 and guides them to a lower delivery chute 22, from which they are dropped into the cup receiving tube 24. The tube 24 is adapted to be removably positioned with relation to the machine, its exact receiving position being determined by means of the stop member 25, which is fixed to the floor on which the machine rests. At the rear of the tube 24 is provided a vertical slot 26 through which extends the arm of a movable support 28 adapted to slide in said slot. This movable support is provided with a bifurcated portion 29 extending inside the tube 24, as shown in Figure 5, and into which is adapted to be placed a removable member 30 provided for the purpose of holding the conical cups which are delivered into the tube 24 in an upright position. For this purpose the member 30 is shaped at its upper end in the form of an inverted cone especially on the interior thereof and which is thereby adapted to correspond with the shape of a conical cup 20.

The movable support 28 is provided with a cylindrical bearing adapted to slide upon a vertically extending post or rod 32, which is positioned directly in the rear of the receiving tube 24 and between the same and a further tube 34, which is likewise cylindrically shaped and adapted to slidably hold therein a piston or weight 36. A rope or cable 38 of suitable material is attached to the weight 36 and is wound about a pulley or drum 40 which is fixed by a key 46 to the axle 47 rotatably mounted in brackets 42 forming part of an extension 44 fixed to the top of the cylinder 36. The cable or rope 38 is wound several times about the pulley or drum 40, in order to prevent slipping of the same thereon and the other end of the cable is attached in a suitable manner to the movable supporting member 28 which slides upon the post 32 and has its bifurcated arm 29 extending inside the slot 26 of the receiving tube 24. The member 28 is further provided with a projection 31 extending rearwardly and adapted to slidably co-act with the exterior of the cylinder 34 in order to maintain the member 28 in proper position on the rod 32.

A toothed wheel or ratchet 48 is likewise mounted on the pin or axle 47 and is fixed thereto by a key similar to the key

46 of the drum 40 so as to rotate therewith. The wheel 48 is provided with teeth 50 with which co-operate pawls 52 and 54. Pawl 54 is mounted on the bracket 42 by means of a pivot pin 56 and is held in position by a spring or the like 58. The pawl 52 is pivotally mounted at 60 on a lever 62 pivoted upon the axle or pin 47, said lever being bifurcated at its ends and having the pawl 62 mounted between this bifurcated portion, as best shown in Figure 3. The bifurcated portion 62 of the lever is connected by means of pins or rivets 64 to a single lever 66 which extends rearwardly therefrom in the direction of the machine 10 and is pivotally connected at 68 with another pivoted lever 70 extending at a right angle thereto and mounted on a bracket 72 extending from the machine proper. The lever 70 has one end pivoted at 74 to the bracket 72 and its other end is pivotally connected at 76 to a link 78 which is likewise pivotally mounted upon the member 80 which is actuated by the machine for the purpose of reciprocating a slidable portion of the feeding table which feeds the prepared blanks to the cup forming dies 12 and 14.

The operation is as follows:

In each reciprocation of the slide which forms part of the feeding table of the machine, the operation of which is fully described in the applications hereinbefore referred to, a blank for forming a cup 20 is fed to the cup forming dies 12 and 14 and a finished cup is ejected therefrom by suitable means. This motion of the feed table slide is accomplished by movement of the member 80 about its pivot point 82, and the link 78 is thereby actuated and its motion moves the lever 70 a short distance in a vertical plane about its pivot point 74. This vertical movement of the lever 70 is transmitted to the bifurcated lever 66, 62, on account of its pivotal connection at 68 with the lever 70.

As the motion of the link or lever 62 is likewise vertical and as the pawl 52 is fixed thereon and actuated by gravity to continually contact with the teeth 50 of the gear wheel 48, it follows that this wheel 48 is moved a predetermined distance each time the feed table slide of the machine 10 is reciprocated and every time a cup is ejected from between the dies, thereby moving the pulley or drum 40 about which the cable 38 is wrapped and allowing the supporting member 28 to drop downwardly a certain predetermined distance at each stroke of the links or levers 70 and 66. It follows that this motion of the drum 40 will operate to raise the weight 36 in the cylinder or tube 34, the downward motion of which is prevented by the action of the spring-controlled pawl 54.

Therefore, every time a cup 20 is delivered into the tube 24 the movable support 28 will be sent downwardly a short distance corresponding to the additional height 5 gained when one of the cups is nested in another, such distance of travel being readily ascertained and easily regulated. After a sufficient number of cups have been transferred into the receiving tube 24 to fill the 10 same, the entire tube 24 may be slid outwardly away from the machine on account of the open bifurcated end 29 of the support 28 and a similar tube having another holder 30 therein may be inserted in position, its particular relation to the machine being readily ascertained by means of the semi-circular stop 25 provided for its proper positioning.

It will be seen that herein is provided a 20 device which receives and automatically stacks paper cups or receptacles which obviously may be of any particular form adapted to nest one within the other and holds these receptacles in such nested position 25 in a receiving tube therefor which can be removed from its proximity to the machine and readily replaced by a similar receiving tube when filled. Afterwards this receiving tube may be emptied of its contents and the same transferred to a carton or similar device for shipping the assembled 30 nested cups.

This invention provides a neat and ready 35 method of assembling the finished cups as they are delivered from the forming machine and holding same in such assembled nested relation conveniently for transfer to a carton for shipment. Furthermore, by the use 40 of this device the necessity of having an extra helper on each machine for the purpose of assembling and gathering up the cups as they are delivered therefrom is avoided and the expense of such labor is practically 45 eliminated.

I am aware that numerous details of construction and operation may be varied through a wide range without departing from the principles of this invention, and I therefore do not purpose limiting the patent granted otherwise than necessitated by the prior art.

I claim as my invention:

1. The combination with a cup forming machine, of counterweighted means connected to be actuated by the machine and adapted to receive a cup and automatically lower the same through predetermined distances.

2. The combination with a cup forming machine, of means having a movable member therein, and a holder on said member within said means adapted to receive and automatically assemble cups as they are delivered from the machine.

3. The combination with an automatic cup

forming machine, of dies thereon for forming cups, a receptacle for receiving the completed cups, delivery means leading from the cup forming dies to said receptacle, and means in the receptacle operable from 70 the machine for stacking and lowering the completed cups within the receptacle.

4. The combination with a cup forming machine, of a slotted receptacle adjacent the machine, a cup holder therein for receiving 75 and stacking completed cups, and a support operable by the machine projecting into the slotted receptacle to support said holder, said receptacle and holder being adapted to be readily withdrawn away from said support when the receptacle is filled.

5. The combination with a cup forming machine, of a receptacle positioned adjacent the machine having a slot therein, a guide rod, a support slidably engaged thereon and 80 projecting into the receptacle through said slot, a cup holder removably engaged on said support within said receptacle to receive and stack completed cups from the machine, a guide tube positioned adjacent said 85 rod, a projection on said support adapted to slidably engage the exterior of said guide tube, a shaft rotatably supported on said guide tube, a drum and a toothed wheel secured on said shaft, a cable engaged around 90 said drum having one end connected to the support, a weight in said guide tube to which the other end of said cable is connected, pawls coacting with said toothed 95 wheel, and a mechanism connected to be 100 actuated by the machine and supporting one of said pawls whereby the toothed wheel and said drum are adapted to be rotated a predetermined amount each time a cup is deposited into said holder to cause lowering 105 of the holder within the receptacle.

6. The combination with a cup forming machine, of a rod adjacent thereto, a cup receiving device slidably engaged on 110 said rod, a pawl operated mechanism connected with said cup receiving device, and means operable from the machine for actuating said mechanism to cause movement of the cup receiving device on said rod each time a cup is deposited onto the 115 device.

7. The combination with a receiving tube having a slot therein, of a movable article receiving support adapted to operate within 120 said slot, and actuating means for moving said support downwardly a predetermined distance after the delivery of an article into the tube.

8. The combination with a receiving tube having a slot therein, of a movable article receiving support adapted to operate within 125 said slot, and actuating means for moving said support downwardly a predetermined distance after the delivery of an article into the tube, said actuating means including a 130

drum, a cable therearound, attached at one end to the movable support and having a counterweight fixed to its other end, and a gear wheel having pawls co-operating therewith adapted to rotate said drum.

9. The combination with a slotted tube, of a movable article receiving support adapted to operate within said slot, and actuating means for moving said support downwardly 10 a predetermined distance after the delivery of an article into the tube, said actuating means including a drum, a cable therearound, attached at one end to the movable support and having a counterweight fixed to its other end, and a gear wheel having pawls co-operating therewith adapted to rotate said drum, the actuating pawl for the gear wheel being fixed to a link, the end of which is vertically reciprocated by means of 20 the reciprocating motion of the blank feeding table of the cup forming machine.

10. The combination with a receptacle for formed articles, of an article support therein, counterweighted means connected therewith, and means for operating the same for automatically lowering said support a predetermined distance each time an article is received by said article support.

11. The combination with a cup forming machine, of a cup receiving and stacking mechanism mounted adjacent thereto, and a pawl actuated mechanism connected to be operated by the machine to cause movement of said cup receiving and stacking mechanism each time a cup is delivered thereto.

12. In combination with an apparatus for receiving and automatically assembling formed articles, a receiving tube having a vertical slot therein, a member adapted to 40 project through said slot, supporting means for the articles adapted to be positioned upon said member in the tube, and automatic means for moving said member and the supporting means to a new receiving position after each delivery of an article thereto.

13. The combination with a cup forming machine, of a reciprocating blank feed table operated from the machine, and a counterweighted cup stacking mechanism operated 50 by said reciprocating blank feed table to automatically stack completed cups as they are delivered from the machine.

14. The combination with a cup forming machine, forming dies thereon for forming 55 cups from blanks, a cup receiving tube adjacent the machine for receiving the cups, a blank feed operating mechanism operated by the machine, and a movable cup receiver in said tube adapted to be operated by said blank feed operating mechanism to receive and assemble the cups as they are delivered into said tube.

15. The combination with a cup assembling device, of a slidable bracket, a cup holder removably engaged thereon, and

means for automatically moving said bracket to a new position after each delivery of a cup into said holder.

16. The combination with a slotted receptacle for formed articles, of a movable bracket projecting therein, an article holder supported thereon within the receptacle, and means connected with the bracket for automatically moving said bracket and holder a predetermined distance each time 75 an article is received by said holder, said slotted receptacle adapted, when filled, to be removed from said bracket.

17. The combination with a cup forming machine, of a guide rod, cup assembling 80 means slidably engaged on said rod, and a slotted cup receptacle adapted to be removably engaged in position to permit the cup assembling means to be moved therethrough.

18. The combination with a cup forming 85 machine, of a vertical guide rod adjacent thereto, cup assembling means mounted thereon, and means operated from the machine for gradually lowering the cup assembling means on said rod.

19. The combination with a cup forming machine, of cup receiving means operated from the machine and adapted to move a predetermined distance each time a cup is 90 delivered thereto.

20. The combination with a cup forming machine, of a member actuated thereby, a pivoted lever, a link pivotally connected to said lever and to said member, a second lever connected to said pivoted lever, a pawl 100 engaged on said second lever, a cup receiving mechanism, and toothed means adapted to be operated by said pawl to move said cup receiving mechanism each time a cup 105 is delivered thereto.

21. The combination with a cup forming machine, of a cup receiving and assembling mechanism connected to the machine, and a pawl and ratchet device operated by the machine for operating the cup receiving and 110 assembling mechanism.

22. The combination with a cup forming machine, of a pulley, a cable engaged therearound, a weight attached to one end of 115 said cable, a cup assembling device connected to the other end of said cable, and means actuated by the machine to cause operation of the pulley and cable to move the cup assembling device each time a cup is delivered thereto from the machine.

23. The combination with a cup forming machine, of a cup assembling attachment therefor, and a cup blank feed mechanism operated by the machine for actuating said cup assembling attachment.

24. In a cup forming machine, the combination with cup forming means, of a reciprocating table for feeding blanks to said forming means to be formed into cups, and mechanisms operable by said reciprocating 130

table for automatically stacking the formed cups.

25. The combination with a machine for forming reinforced receptacles, of receptacle discharging means operated from the machine, and an automatic receptacle stacking attachment also operated from the machine.

In testimony whereof I have hereunto subscribed my name in the presence of two subscribing witnesses.

PETER T. POTTS.
